HAND GRIPPER FOR HOLDING FISH

Arnold L. Gravning, 1150 E. Shelley St.,
Manhattan Beach, Calif.

Filed Oct. 19, 1959, Ser. No. 57,978

Term of patent 14 years

(Cl. D31—4)

Fig. 1.

Fig. 2.

Fig. 3.

Fig. 4.

Fig. 1 is a front perspective view of a hand gripper for holding fish embodying my new design;

Fig. 2 is a top plan view thereof,

Fig. 3 is a rear elevational view thereof, and

Fig. 4 is a left side elevational view thereof.

I claim:

The ornamental design for a hand gripper for holding fish, as shown.
